UNITED STATES PATENT OFFICE.

ROBERT R. BAILEY, OF CHICAGO, ILLINOIS.

CIGAR-DRILL.

1,345,736.

Specification of Letters Patent.

Patented July 6, 1920.

Application filed April 14, 1919. Serial No. 289,978.

To all whom it may concern:

Be it known that I, ROBERT R. BAILEY, a citizen of the United States, residing at Chicago, in the county of Cook and State of Illinois, have invented certain new and useful Improvements in Cigar-Drills, of which the following is a specification.

My invention relates to a device for drilling a hole in the tip of a cigar so that it may be smoked without cutting off the tip.

The common practice, before lighting a cigar to smoke, has been to cut off the tip of the cigar so it will draw. After the tip has been cut off the wrapper or binder begins to unwind and gradually becomes loosened so that more or less tobacco is chewed while the cigar is being held in the mouth and smoked. This objection has been recognized for a long time and various devices have been constructed to pierce or cut a hole in the end of a cigar, but such devices have been either complicated and, therefore, expensive to manufacture, or have not accomplished the desired result. In piercing a cigar the spear is forced axially into the tip which results in the tobacco being wedged or compressed around the spear, the tobacco remaining in that condition after the spear has been withdrawn and in such condition the cigar will not draw well.

The object of my invention is to provide a device which will be of simple construction, inexpensive to manufacture, easy and convenient to manipulate, and which will bore or drill a hole in the tip of a cigar, remove therefrom the tobacco pulverized by the drilling operation, and leave the tobacco around the bore loose so that the cigar will draw as freely as though the tip had been cut off, but without the resultant tendency of the binder becoming loose and unwinding.

My invention will be better understood by reference to the accompanying drawing, illustrating certain preferred embodiments, in which:

Figure 1 is a side elevational view embodying certain principles of my invention;

Fig. 2 is an enlarged end elevational view of the device shown in Fig. 1, looking toward the end adapted to receive the tip of a cigar;

Fig. 3 is an enlarged longitudinal sectional view of the device;

Fig. 4 is a cross sectional view taken on the line 4—4 of Fig. 3.

Like characters of reference designate like parts in the several views.

Referring first to Figs. 1 to 4 inclusive, the cigar drill comprises a tubular body member 10 and a twist drill 11 axially disposed therein and mounted in one end of the rotatable and longitudinally movable shaft 12 on the other end of which a handle 13 is provided. One end of the tubular body member is enlarged and is provided with a bell-shaped recess 14 adapted to receive the tip of a cigar and the other end is formed with an axial bore 15. The inner end of the shaft 12 is enlarged, but smoothed off so it will rotate and slide freely within the bore 15, and forms a bearing for the drill. The tubular body member is provided with an aperture 16 in the bottom of the recess 14 through which the drill may project, which aperture serves also as a bearing or guide for the drill. The handle 13 may be knurled to facilitate turning the same. Preferably a plurality of apertures 17 are provided in the tubular member at the end of the bore, so that the tobacco pulverized by the drilling operation may sift out when the drill is withdrawn from the cigar. After the drill has been mounted in the end of the shaft 12 the parts are placed in the tubular member and the small end of the tubular member turned over by spinning to form a shoulder 18 to hold the parts in place. The drilling operation is performed by first pressing the tip of a cigar into the bell-shaped recess 14 and then turning the drill 11 until the handle 13 travels up to the end of the body member. The drill may then be twirled back and forth a few times to clear the hole formed in the end of the cigar of the pulverized tobacco.

I claim:

A cigar drill comprising, in combination, a member, one end of which is in the form of a hollow cylinder and the other end in the form of a substantially conical socket, adapted to receive the closed end of a cigar, which is rigid with the cylinder and has a

100

bore opening into the same, a guide plunger loosely fitting into the cylinder so that it may be rotated or moved back and forth by movements independent of each other, a 5 twist drill rigidly connected with said plunger and adapted to be projected through the bore into the socket, and a stem rigidly connected with the plunger extending

through the other end of the cylinder whereby the drill may be forced through the 10 end of a cigar in the socket by a twisting movement and withdrawn from the same by a straight longitudinal movement to make a clean perforation in the end of the cigar.

ROBERT R. BAILEY.
